UNITED STATES PATENT OFFICE.

CHARLES L. BARTHOLOME, OF TERRE HAUTE, INDIANA.

CLAMPING DEVICE FOR CLOTHESLINES.

1,425,313.

Specification of Letters Patent. Patented Aug. 8, 1922.

Application filed May 6, 1922. Serial No. 558,971.

To all whom it may concern:

Be it known that I, CHARLES L. BARTHOLOME, a citizen of the United States, residing at Terre Haute, in the county of Vigo and State of Indiana, have invented certain new and useful Improvements in a Clamping Device for Clotheslines, of which the following is a specification.

My invention relates to a clamping device 10 for holding a wash line taut, and to permit of the adjustment of the wash line, when desired.

An important object of the invention is to provide a device of the above mentioned 15 character, which is of simplified construction, adjustable for coaction with wash lines of different diameters, and is strong and durable.

Other objects and advantages of the invention will be apparent during the course 20 of the following description.

In the accompanying drawings forming a part of this specification, and in which like numerals are employed to designate 25 like parts throughout the same,

Fig. 1 is a side elevation of a clamping device embodying my invention,

Fig. 2 is a front elevation of the same, and,

Fig. 3 is a plan view of the device.

30 The clamping device embodies a body portion 5, which is preferably hollow. This body portion includes a back 6 having openings 7, for the reception of screws, whereby the body portion may be held to a post 35 or like support, in a vertical position. The body portion includes sides 8, spaced as shown.

The sides 8 are provided with forwardly 40 extending stationary jaws 9, forming recesses or pockets 10, as shown. These jaws are spaced, as shown in Fig. 2, to cooperate with a wedge, to be described.

The numeral 11 designates a block, slideable 45 within the upper portion of the hollow body portion 5, between the sides 8. This block is preferably hollow and is provided near its upper end with outwardly extending pins 12, operating within longitudinal slots 13, in the sides 8. The block 11 carries 50 a wedge element 14, tapering downwardly, as shown in Figs. 1 and 2. This wedge is adapted to approach the jaws 9, and passes between them, and clamps the rope within the pockets 10, and the jaws 9.

55 The block 11 is provided at its lower end with arms 15, preferably integral therewith,

pivotedly connected by means of a pin 16 with the link 17. This link extends downwardly between the forked ends of a lever 18, and is pivoted at 19, to ears 20 formed 60 integral with the sides of the lever. The ends 21 of the lever carry outwardly projecting pins or pivots 22, projecting into slots 23, and adapted to be shifted into selected spaced notches 24.

65 In the use of the device, the body portion 5 may be vertically arranged, and the rope A may be placed within the pockets 10 of the jaws 9. The pins 22 being inserted in the selected notches 24, the lever 18 is swung 70 downwardly, and the link 17 draws the wedge element 14 downwardly, to clamp the rope to the jaws 9. The lever 18 is swung downwardly to lie within the lower portion 75 of the body portion 5, and is swung past the dead center, and hence will not be accidentally displaced.

It is to be understood that the form of my invention herewith shown and described, is to be taken as a preferred example of the 80 same, and that various changes in the shape, size, and arrangement of parts may be resorted to without departing from the spirit of my invention or the scope of the subjoined claims.

85 Having thus described my invention, I claim:

1. A rope clamping device comprising a body portion having stationary jaws, a wedge element movable longitudinally of 90 the body portion toward and away from the jaws, and means to move the wedge element, said means comprising a pivoted lever adjustably mounted upon the body portion to be shifted longitudinally thereof, and a link 95 connecting the lever and the wedge element.

2. A rope clamping device comprising a hollow body portion having spaced sides, said sides carrying jaws and also having longitudinal slots, a wedge element movable 100 longitudinally within the hollow body portion and having pins entering the longitudinal slots, a pivoted lever adjustably mounted upon the body portion to be shifted longitudinally of the body portion, and a link 105 connecting the lever and wedge element.

3. A rope clamping device comprising a hollow body portion provided with spaced sides, said sides having stationary jaws forming pockets, said sides being provided 110 upon one side of the jaws with longitudinal slots and upon the opposite side of the jaws

- with longitudinal slots having transverse notches in communication therewith, a block 5
slidable in the hollow body portion and having a wedge and provided near one end with pins 10
slidable within the first named longitudinal slots, a forked lever having its forked end extending into the hollow body portion and carrying pins to operate within the second named slots and to be shifted into selected notches, and a link extending through the forked end of the lever and pivotally connected with the lever and also pivotally connected with said block.
4. A rope clamping device comprising a hollow body portion provided with spaced sides, said sides having stationary jaws 15
- forming sockets, said sides being provided upon one side of the jaws with longitudinal slots and upon the opposite side of the jaws with longitudinal slots having transverse notches in communication therewith, a block 20
slidable in the hollow body portion and having a wedge and provided with pins 25
slidable within the first named longitudinal slots, a lever extending into the hollow body portion and having extensions to operate within the second named slots and to be shifted into selected notches, and a link pivotally connecting the lever with the block.

In testimony whereof I affix my signature. 30

CHARLES L. BARTHOLOME.
